UNITED STATES PATENT OFFICE.

CARL J. LANDIN, OF BOSTON, MASSACHUSETTS, ASSIGNOR TO UNIVERSAL APPLIANCE COMPANY, OF BOSTON, MASSACHUSETTS, A CORPORATION OF MASSACHUSETTS.

TELEPHONE-SUPPORT.

1,119,782.

Specification of Letters Patent.

Patented Dec. 1, 1914.

Application filed June 10, 1914. Serial No. 844,346.

To all whom it may concern:

Be it known that I, CARL J. LANDIN, a citizen of the United States, residing at Boston, county of Suffolk, State of Massachusetts, have invented an Improvement in Telephone-Supports, of which the following description, in connection with the accompanying drawing, is a specification, like characters on the drawing representing like parts.

This invention relates to a support capable of sustaining a telephone or other object and has for its object to provide a novel device of this nature which is simple and inexpensive to manufacture; which can be applied to any article of furniture, to a wall, or to a floor, and which will permit the telephone instrument or other article supported thereby to be moved up and down, in and out and laterally in either direction, or in any combination of these three directions, and which will automatically hold the telephone instrument counterbalanced in any position in which it is left.

In order to give a proper understanding of my invention I have illustrated in the drawing a selected embodiment thereof which is in the nature of a telephone support and which will now be described, after which the novel features will be pointed out in the claims.

Figure 1 of the drawing is a side elevation showing a device embodying my invention; Fig. 2 is an enlarged section on the line $x-x$, Fig. 1.

My improved device comprises a supporting standard, a supporting arm capable of supporting a telephone or other article but which is hereinafter referred to as a telephone-supporting arm inasmuch as the illustrated embodiment of the invention is a telephone support, means for connecting said arm to said standard at two different points, one of said connections being capable of moving horizontally or out-and-in, and the other being capable of moving vertically only, and a counterbalancing member acting on said telephone-supporting arm and adapted to counterbalance it in any position. In the preferred embodiment of my invention the connection between the telephone-supporting arm and the supporting standard is constituted by two parallel links pivoted to said arm and connected together, the lower end of one of which links

is connected to the supporting standard so as to move out and in while the lower end of the other link is connected to said standard to move up and down. This combination of parts provides a device which permits the telephone instrument sustained on the telephone-supporting arm to be moved in and out, or up and down, or laterally, or in a direction which combines two or more of the above motions, thus making the device one which is useful in its action and by which the telephone can be supported in any desired position. In the illustrated embodiment of my invention the supporting standard is shown at 1 and it is sustained in a bracket 2 that is fixed to a support 3 which may be a desk, wall or any other device. The standard 1 is mounted for turning movement in the bracket 2 and is made so that it can be readily removed from the bracket. As herein shown, the lower end of said standard is loosely received in a bore in the bracket and said standard is provided with a collar 4 which rests on the bracket and which holds it in vertical position.

The telephone-supporting member is shown in the form of an arm 15 to the end of which the telephone instrument 17 is secured in any suitable way, a clamp 16 being provided for that purpose, which clamp is swiveled to the end of the supporting member 15 by a universal joint connection 18. Pivoted to the supporting member 15 at 19 and 20 are two parallel links 11 and 12, said links being connected at their lower ends by a link 13. The link 11 is connected to the supporting standard 1 in such a way as to permit the lower end of said link to move up and down only relative to the standard, while the other link 12 is connected at its lower end to the standard in such a way as to permit said lower end to move out and in only. While any suitable connection between the links and the standard to permit the vertical movement of one link and the out and in movement of the other link may be provided, I have herein shown for this purpose two sleeves 7 and 8, the sleeve 7 being pivotally connected to the link 11 and slideable vertically on the supporting standard 1, while the sleeve 8 is pivotally connected to the lower end of the link 12 and is mounted for lateral or out and in movement on the standard. This is herein provided for by forming the stand-

ard with the laterally-extending arm 5 on which the sleeve 8 is slidably mounted, and this arm is shown as being formed by bending the upper end of the standard 1 laterally, as shown at 6 and then bending the 5 end of the portion 6 backwardly on itself to present the laterally-extending arm 5.

The sleeve 7 has connected thereto a counterbalancing member herein shown in the 10 form of a spring 21 which encircles the standard 1 and is connected at its upper end to said sleeve and at its lower end to the standard, as shown at 22.

With the construction as thus above described, it is possible to move the telephone 15 up or down in a substantially vertical plane or to move the telephone in or out horizontally or right and left, or to combine all of these motions and yet have the telephone automatically held and maintained in any 20 position in which it is left. The full lines in Fig. 1 show the telephone raised and out of the way. The telephone may be brought down into convenient position for use in a 25 substantially vertical direction by simply drawing downwardly on the telephone instrument, this operation swinging the supporting member 15 about the point 20 as a pivot and drawing the sleeve 7 upwardly on 30 the standard 1 against the action of the spring 21. In this case the link 12 constitutes a strut which acts as a pivotal member or fulcrum for the lever 15. The position of 35 the telephone support when the above operation is performed is shown in the dotted lines Fig. 1. The telephone can also be drawn outwardly away from the support 3 at the same time that it is lowered by bringing the parts out to the position shown by 40 the dot and dash lines, Fig. 1. This is done by drawing downwardly and forwardly on 45 the telephone instrument, which operation results in causing the sleeve 8 to slide outwardly on the arm 5 at the same time that the sleeve 7 slides upwardly on the stand 1. The tension of the spring 21 counterbalances the weight of the telephone even when 50 the parts are in the position shown by the dot and dash lines and will thus maintain 55 the parts in this position. While the telephone is in the position shown by the dot and dash lines Fig. 1, it may be pushed back without raising it, this operation resulting 60 in swinging the parallel links 11 and 12 into their vertical position and the sleeve 8 along the arm 5 into the full line position. Furthermore because of the fact that the standard 1 is swiveled in the bracket 2 it is possible to swing the telephone instrument 65 into any position to the right or the left of that shown in the drawings.

The link 11 is shown as provided with a projection 25 which is adapted to engage the link 12 and thus limit the backward swinging 65 movement of the telephone. Both links

11 and 12 may be forked at their lower ends so that when they are moved forwardly into the dot and dash line view Fig. 1 the two arms of each link will straddle the part 6 of the stand. Said part 6 thus constitutes a 70 guide for the links and serves to maintain them in proper relative position.

In order to maintain the telephone instrument in proper balance when the receiver is removed from its hook and its 75 weight is thus taken off from the telephone-supporting arm 15, I have provided a friction device associated with the link 11 and which applies sufficient frictional pressure to the supporting standard to counteract or 80 offset the weight of the telephone receiver. In the illustrated embodiment of my invention this friction device is in the form of a spring-pressed friction block 23 which occupies a recess in the sleeve 7 and is yieldingly held against the standard 1. The 85 spring 24 which acts on the block 23 will have such a tension that the friction of the block against the standard will be sufficient to counteract the weight of the telephone receiver so that when the telephone instrument 90 is relieved of the weight of the receiver the position of the supporting arm as maintained by the counterbalancing spring will remain unchanged.

It will be noted from the above that my 95 device comprehends a telephone-supporting arm which is pivotally connected at two points with the supporting-standard, one of said connections having a capacity for 100 movement out and in while the other of said connections has a capacity for vertical movement only, together with a counterbalancing means acting on said arm to hold the telephone in any position in which it 105 may be placed. Moreover, the device herein 110 illustrated is very simple in construction and can be inexpensively manufactured.

While I have illustrated a preferred embodiment of the invention I do not wish to 115 be limited to the constructional details shown. It will also be obvious that the construction herein illustrated is capable of supporting other articles than telephones and while I have referred to the member 15 120 as a telephone-supporting member, I desire to state that I have used this term as illustrative and not as defining any limitation as to the use of the device. Hence I do not wish to be limited to the use of the device 125 for supporting telephones.

Having fully described my invention, what I claim as new and desire to obtain by Letters Patent, is:

1. In a telephone support, the combination 125 with a supporting standard, of a telephone-supporting member, two parallel connected links both pivotally connected to said telephone supporting member, a pivotal sliding connection between the lower end of 130

each link and the supporting standard, one of said connections permitting a vertical sliding movement and the other an in-and-out movement, and counterbalancing means 5 acting on one of said links.

2. In a telephone support, the combination with a supporting standard, of a telephone-supporting member, two parallel connected links both pivotally connected to said 10 telephone supporting member, means movably connecting the lower end of each link to said supporting standard, the connection for one link permitting movement thereof in a vertical direction and the connection for 15 the other link permitting movement thereof in a lateral direction, and counterbalancing means acting on one of said links.

3. In a telephone support, the combination with a supporting standard, of a telephone-supporting member, two parallel connected links both pivotally connected to said telephone supporting member, means movably connecting the lower end of each link to said supporting standard, the connection for 20 one link permitting movement thereof in a vertical direction and the connection for the other link permitting movement thereof in a lateral direction, and counterbalancing means acting on the vertically movable link. 25

30 4. In a telephone support, the combination with a standard having a laterally-extending arm, of a telephone-supporting member, two parallel links, both pivotally connected to said telephone-supporting member, means connecting one link to the laterally-extending arm to permit said link to move longitudinally of the arm and means connecting the other link to the standard to permit it to move vertically thereon, a connection between said links, and counterbalancing means acting on the latter link. 35

40 5. In a telephone support the combination with a standard having a laterally-extend-

ing arm, of a sleeve slidable vertically on the standard, another sleeve slidable laterally on said arm, a telephone-supporting member and parallel links both pivotally connected to said supporting member and one pivoted to each of said sleeves. 45

6. In a telephone support the combination with a standard having a laterally-extending arm, of a sleeve slidable vertically on the standard, another sleeve slidable laterally on said arm, a telephone-supporting member, parallel links both pivotally connected to said supporting member and one pivoted to each of said sleeves, and a counterbalancing device connected to one of said sleeves and acting to counterbalance the weight of a telephone in any position 60 thereof. 55

7. In a telephone support in combination with a standard having at its upper end a laterally-extending arm, of a sleeve slidably mounted on said standard, means to provide 65 frictional engagement between the sleeve and standard, a telephone-supporting member, two parallel links pivoted to said supporting member one of said links being pivoted to said sleeve, and a pivotal sliding 70 connection between the other link and said laterally-extending arm. 75

8. In a support, the combination with a supporting standard having a vertically and a horizontally-extending guiding portion, of a guiding member movable on each guiding portion, and a supporting arm pivotally connected to each guiding member, and counterbalancing means acting on said arm. 80

In testimony whereof, I have signed my name to this specification in the presence of two subscribing witnesses.

CARL J. LANDIN.
